UNITED STATES PATENT OFFICE.

GEORGE F. STEEDMAN, OF ST. LOUIS, MISSOURI.

FLUID-ACTUATED CUSHIONED HOIST.

No. 840,877.

Specification of Letters Patent.

Patented Jan. 8, 1907.

Application filed December 4, 1905. Serial No. 290,180.

To all whom it may concern:

Be it known that I, GEORGE F. STEEDMAN, a citizen of the United States, residing at St. Louis, Missouri, have invented a certain new and useful Improvement in Fluid-Actuated Cushioned Hoists, of which the following is a full, clear, and exact description, such as will enable others skilled in the art to which it appertains to make and use the same, reference being had to the accompanying drawings, forming part of this specification, in which—

Figure 1 is a diagrammatical view of a single-acting regulated cushioned hoist constructed in accordance with my invention. Fig. 2 is a diagrammatical view of a double-acting regulated cushioned hoist. Fig. 3 is a diagrammatical view of a balanced regulated cushioned hoist. Fig. 4 is a fragmentary side elevational view of a portion of the cylinder, showing the specific form of regulating device, and Fig. 5 is a vertical longitudinal sectional view through the regulating-device casing.

This invention relates to fluid-actuated hoists in which a cylinder is employed for containing a piston to be actuated by a suitable fluid, preferably air.

The object of the invention is to construct a fluid-actuated hoist the speed of whose piston under no load, as well as under full load, may be regulated independently of the operating-valve and in such a manner that the piston will automatically slow down and gradually come to rest at the extremities of its stroke independently of the manipulation of the regulating-valve.

Broadly stated, the invention is carried out by means of a speed-regulating device, as illustrated in a companion application executed by me of even date herewith and given Serial No. 290,179, the characteristic feature of this invention residing in the addition of an air-cushioning device at the ends of the cylinder and means for regulating the cushion.

As illustrating the principle of my invention I have shown in Fig. 1 a cylinder 1, having contained therein a piston 2, with an outwardly-projecting stem 3. A supply-tube 4 has in its path a three-way valve 5, which may be operated to direct a flow of fluid, such as air, into one end of the cylinder through the inlet-tube 6, or it may be turned, as indicated in Fig. 1, to exhaust from the end of the cylinder, as the case may require.

Interposed between the tube 4 and the cylinder is a loop consisting of two branches 7 and 8. The branch 7 is provided with a check-valve 9 of ordinary construction and is so arranged that it is capable of opening only to admit the air into the cylinder 1 by flowing in the direction indicated by the arrow. A similar but oppositely-opening check-valve 10 is arranged in the branch 8, and this check-valve is permitted to open only when the fluid flows in the direction indicated by the arrow adjacent the valve 10 and out through the exhaust, as will be presently explained.

11 and 12 designate cocks in the respective branches 7 and 8, which may be manipulated so as to regulate the size of either of the openings in either of the branches 7 and 8, so as to control the amount of air flowing therethrough.

In the end of the cylinder opposite the tube 4 is a ported tube 13, having an inwardly-opening check-valve 14 therein, and in the same end of the cylinder is illustrated a valved tube 15. In communication with the inlet-openings of the cylinder 1 and the tube 6 is a branch 16, having a regulating-valve 17 therein, which is adapted to be regulated so as to govern the volume of air passing through the branch 16, which branch 16 is what might be termed a "cushion-control." 8^a designates an exhaust-tube near the upper end of the cylinder and corresponds to the branch 8, which tube 8^a is provided with a regulating-valve 10^a and an outwardly-opening check-valve 12^a.

The operation of the device in the form illustrated in Fig. 1 is as follows: Suppose the valve 5 is turned to admit air through the branches 7 and 16 into the cylinder. The opening in valves 15 and 17 is so small that it may be disregarded except for its cushioning function. Air cannot pass through the branch 8 to act upon the piston in the cylinder, for the reason that the outwardly-opening check-valve would prevent it; but it must pass through the branch 7 into the cylinder, so as to actuate the piston within the cylinder to move it from the end adjacent the branch 7 toward the opposite end. The speed of hoisting or the inward motion of the piston will depend upon the load to be lifted and the size of the openings made by the valves 11 and 10^a. For the maximum load on the piston-rod 3 the valve 11 will be adjusted so as to give proper speed, the valve 10^a meantime being fully open. For the

minimum load on rod 3 the adjustment of the valve 11 will be unchanged, the speed of the hoist being regulated by the valve 10^a. By a harmonious adjustment of valves 11 and 10^a the speed of hoisting is made approximately uniform irrespective of the load. It is to be understood that in the operation the check-valves 10 and 14 cause the tube 13 and branch 8 to be temporarily inoperative; 10 also, that the valve 5 is in a wide-open admitting position.

It will be assumed that the cylinder is arranged in a vertical plane and that the operation just described has resulted in raising 15 the piston. Now if it is desired to lower the piston or to permit it to descend, the valve 5 will be operated so that its port 18 will register with an exhaust-port 19 in its casing and with the loop formed by the branches 7 and 8.

In order to cause the port 18 to register with the exhaust-port 19 in the valve-casing, it will be necessary to cut off communication 20 between the loop and the supply-pipe 4. In this position of the valve the fluid can pass from the bottom of the cylinder through the branch 8 and through the valve-plug and then to atmosphere. The exhaustion of the cylinder through the branch 8 will continue 25 until the lower end of the piston 2 reaches a position to register with the branch 8, when the exhaust through the branch 8 will be promptly cut off. When it is considered that the branch 8 is positioned a short distance 30 from the end of the cylinder, it will be appreciated that a volume of air will still remain in the cylinder equal to the inner area of the cylinder times the distance from the lower face of the piston to the inner face of the lower end of the cylinder. This volume 35 of air will represent the cushion, and as it cannot exhaust through the branch 8 (on account of the fact that communication with the branch has been cut off) and as it cannot exhaust through the branch 7 it must exhaust 40 through the branch tube 16. Now as the branch 16 is in communication with the pipe 6 and with the port 19 of the valve-casing the speed at which the cushion is destroyed 45 will depend upon the adjustment of the valve 17, which controls the size of the opening through which the air will pass.

In ascending the air will exhaust through the pipe 8^a until communication between the cylinder and said pipe is cut off in the same manner as has been described in connection with the branch 8, and as soon as communication is cut off in the branch 8^a a cushion will be formed at the upper end of the cylinder, the air forming the cushion exhausting 55 through the valved tube 15.

From the foregoing it will be seen that the speed intermediate the ends of the cylinder may be controlled to suit the purposes of the operator, but irrespective of the speed at

which the piston travels it will automatically slacken and gradually come to a stop before reaching the end of its stroke. In actual practice I have demonstrated that this stopping will be so gradual as to be practically 70 free from any jar or objectionable vibration which under ordinary circumstances might be communicated to the load carried by the piston-stem 3.

In the form of hoist just described, which 75 I designate as "single-acting," the actuating fluid enters the lower or piston-rod end of the cylinder only.

From the foregoing description it will be seen that in general I regulate the speed of 80 hoisting and lowering the variable load by providing an adjustable force resisted by an adjustable resistance thereto, which in practice I have found to produce regulation many times more effective than the regulation 85 of either the force or the resistance separately, and combined with the many advantages resulting therefrom I apply a regulating-cushion designed to prevent sudden jars or shocks from being communicated 90 to the load by the piston when it reaches either extremity of its stroke.

In Fig. 2 I have illustrated what I designate as a "double-acting" hoist. The difference between the forms illustrated in 95 Figs. 1 and 2 is that in Fig. 1 the piston is permitted to gravitate from the upper to the lower end of the cylinder, while in Fig. 2 air is admitted at the respective ends of the cylinder at different times, and the pipe 6 is 100 illustrated as being in communication with the four-way valve 20, the casing of which is also in communication with the supply-pipe 4. A pipe 6^a is in communication with the valve-casing, and instead of the valved 105 tubes 8^a, 13, and 15 I substitute a duplicate arrangement of tubes and valves similar to that described for the lower portion of the cylinder shown in Fig. 1, the operation of which is so similar thereto as not to need 110 further explanation.

In Fig. 3 I have illustrated a construction which I term a "balanced-cushioned" hoist. The cylinder, piston, and other accessories, including the tubes, valves, &c., are substantially the same as those illustrated in Fig. 2, with the exception that the tube 6 is in communication with a reservoir 22, which reservoir is also in communication with the tube 6^a, in the path of which is a three-way 120 valve 5^a, similar to the one illustrated in Fig. 1. An elevator-car 3^a is also illustrated as being adapted to be raised and lowered by the piston 2 through the medium of the rod 3. In this form (illustrated in Fig. 3) the 125 valve 5^a is shown in a position to equalize the pressure in all parts of the cylinder, and this will be the case, because, although the tank 22 is under pressure, the inlet-openings to both ends of the cylinder are in commun- 130

nication with the tank through the respective pipes 6 and 6^a, and the same pressure will be exerted on both sides of the piston 2. However, the area of the upper face of the piston 5 against which the pressure will be exerted will be slightly in excess of the resisting area of the lower face of the piston, due to the fact that the piston-rod is connected to the lower face of the piston. In other words, 10 the resisting area of the upper face of the piston will be equal to the resisting area of the lower face of the piston plus the cross-sectional area of the piston-rod. It therefore follows that if the same pressure exists 15 in the cylinder on both sides of the piston and a greater area of resistance exists on the upper face of the piston the tendency of the piston will be to descend, even when no load is carried by the rod, and this tendency to 20 descend is augmented by the weight of the rod, and additionally so by any weight carried by the rod. Thus if the valve 5^a is in the position indicated in Fig. 3 and the piston happened to be at the upper end of the cylinder 25 in an obvious manner. When it would be desirable to hoist the load, the valve 5^a would be operated to throw the port of the valve into communication with the exhaust- 30 port of the casing, so that the air could exhaust from the top of the cylinder to atmosphere, and communication between the pipe 6^a and the reservoir 22 would be cut off, so that all of the pressure in the tank would be 35 exerted against the lower face of the piston, so as to raise it. The cushioning of the piston, however, would in no wise be affected by this operation.

In Figs. 4 and 5 I have illustrated a particular form of regulating device in which the 40 inlet and outlet valves, together with the cushioning device, are all arranged in a common casing. In order to disclose the application of the device illustrated in Figs. 4 and 45 5 as applied to the cylinder and in lieu of the branch pipes and valves heretofore described, I have designated the inlet-pipe 23, which is in communication with a casing 24, having 50 valve-seats 25 and 26, on which are check- valves 27 and 28, the valve 27 permitting communication between the tubes 29 and 23 and the oppositely-opening check-valve 28 permitting communication between the tubes 30 and 23. Springs 31 and 32 are 55 seated on the respective check-valves and bear against stuffing-boxes 33 and 34, respectively. These springs have a tendency to maintain the valves on their seats and to reseat them when they have been unseated. 60 Passing through the stuffing-boxes are adjusting-screws 35 and 36, which serve as regulating devices for regulating the distance the check-valves are capable of moving off their seats, and thereby regulating the size of 65 the passage of communication between the

tubes 29 and 30 with the tube 23. Adjacent to the tube 30 is a threaded port 37, with which a threaded regulating device or screw 38 is adapted to coact to regulate the cushioning. The tube 29 being in communication 70 with the cylinder at a point a slight distance from the end thereof and the tube 30 being in communication with the cylinder at the extremity thereof, the operation will be as follows: The air will be admitted through the 75 tube 23 and will pass up through the opening normally closed by the valve 28 into the tube 30, and thence to the cylinder. If the air is admitted to the other end of the cylinder, the piston will be moved in the direction of the 80 arrow and the air will exhaust through the pipe 29, through the opening normally closed by the valve 27, and then into the pipe 23 to the exhaust. As soon as the piston reaches a point in the cylinder opposite the opening 85 of the pipe 29 communication with the pipe 29 will be cut off, and the cushioned air between the piston and the end of the cylinder will be forced through the pipe 30 and the pressure will have a tendency to maintain 90 the valve 28 on its seat, so its only escape can be through the opening 37. As the regulating device 38 is controllable to regulate the size of the opening 37, the cushion may be 95 regulated.

In describing the above invention I have purposely referred to each part and described it specifically, so that the operations of the various forms might be easily understood, and the cylinders have been described as being of the vertical type, in which the piston has a descending and ascending movement. However, I reserve the right to arrange the cylinders horizontally or at any other angle, if desired, and whenever the terms "vertical," "ascending," and "descending" are employed I would have it understood that they are not to be construed literally, but are used merely for the sake of distinguishing one movement from the other.

Having thus described the invention, what is claimed as new, and desired to be secured by Letters Patent, is—

1. In a device of the class described, the combination of a cylinder, a piston therein, 115 an inlet-pipe in communication with the end of the cylinder, an exhaust-pipe intermediate the ends of the cylinder and in communication therewith, the communication being cut off by the piston when the piston is adjacent 120 to the exhaust-pipe, means for exhausting the fluid existing between the end of the cylinder and the piston after the communication with the exhaust-pipe has been cut off, and a regulating device in said last-named means; 125 substantially as described.

2. In a device of the class described, the combination of a cylinder, a piston therein, an operating-valve, a tubular connection between the valve and the cylinder, said tubu- 130

lar connection being divided into connecting-passages, means for cutting off communication between the cylinder and valve in one of the passages when the other passage is open, 5 and a regulating cushion device communicating with one end of the cylinder; substantially as described.

3. In a device of the class described, the combination of a cylinder, a piston therein, 10 an operating-valve, a tubular connection between the valve and the cylinder, said tubular connection being divided into connecting-passages, means for cutting off communication between the cylinder and valve in one of the 15 passages when the other passage is open, said piston being movable into position to cut off communication between the other passage and the cylinder, a secondary exhausting means communicating with the end 20 of the cylinder and constructed so as to continue to exhaust after communication with said other passage has been cut off, whereby a cushion may be provided for the piston near the end of the cylinder due to the volume of 25 air existing between the end of the cylinder and the piston, and means in the secondary exhaust for regulating the exhaust from said cylinder; substantially as described.

4. In a device of the class described, the combination of a cylinder, a piston therein, 30 an operating-valve, a tubular connection between the valve and the cylinder, said tubular connection being divided into connecting-passages, means for automatically cutting off communication between the cylinder and valve in one of the passages when the other 35 passage is open, and a cushioning exhausting device in communication with the end of the cylinder; substantially as described.

5. In a device of the class described, the combination of a cylinder, a piston therein, an operating-valve, a tubular connection between the valve and the cylinder, said tubular connection being divided into connecting-passages, oppositely-opening check-valves in 45 said passages, and a valved exhaust-port in communication with the end of said cylinder; substantially as described.

6. In a device of the class described, the combination of a cylinder, a piston therein, 50 an operating-valve, a tubular connection between the valve and the cylinder, said tubular connection being divided into connecting-passages, a check-valve in one passage opening 55 toward the cylinder, a check-valve in the opposite passage opening toward the operating-valve, and an exhaust-port in communication with the end of the cylinder and permitting exhaust of the fluid from the cylinder 60 when both check-valves are closed; substantially as described.

7. In a device of the class described, the combination of a cylinder, a piston therein, 65 an operating-valve, a tubular connection between the valve and the cylinder, said tubu-

lar connection having independent connecting-ports, means for regulating the size of each port, means for cutting off communication between both ports, and an exhaust-port in communication with the cylinder 70 which is capable of continuing the exhaust when communication between both ports and the cylinder is cut off; substantially as described.

8. In a device of the class described, the combination of a cylinder, a piston therein, 75 an operating-valve, a tubular connection between the valve and the cylinder, said tubular connection being divided into independent connecting-passages, oppositely-opening 80 check-valves in the respective passages, means for regulating the size of each passage, and a valved exhaust in communication with one end of the cylinder; substantially as described.

9. In a device of the class described, the combination of a cylinder, a piston therein, an operating-valve, a tubular connection between the valve and the cylinder, said tubular connection being divided into separate 90 branches one of which is a supply to the cylinder and the other an exhaust, means for automatically closing one branch when the other is open, means for regulating the size of the port in each branch, the piston being 95 movable into position for closing the open branch whereby both branches will be closed, and an exhaust-port through which the air may be continued to exhaust when both branches are closed; substantially as described.

10. In a device of the class described, the combination of a cylinder, a piston therein, an operating-valve, a tubular connection between the valve and the cylinder, said tubular connection being divided into separate 105 branches, one of which is a supply to the cylinder and the other an exhaust, the exhaust branch being adapted to be closed by the movement of the piston, and a secondary exhaust in communication with the cylinder and operable after the exhaust branch is 110 closed; substantially as described.

11. A regulating device of the class described having a port adapted to alternately 115 receive and discharge a fluid, said regulating device having an exhaust-port in communication with said first-named port through which the fluid will flow in exhausting, all other sources of communication with said 120 first-mentioned port being closed; substantially as described.

12. A regulating device of the class described comprising a casing, supply and exhaust ports in communication with said casing, a third port in communication with both 125 said first-mentioned ports, and means for valving the first-mentioned ports, said casing having a port in communication with said supply-port and to one side of the valved 130

portion of said port; substantially as described.

13. The combination with a cylinder, and a source of fluid-supply, a piston in said cylinder, a supply-tube in communication with said cylinder, an exhaust-tube in communication with said cylinder, a regulating device, the casing of which is in communication with both tubes, oppositely-opening check-valves in said regulating device affording communication between one of said tubes and the source of supply when the other of said tubes is closed, said casing having an exhaust-port between the supply-port valve and the discharge end of the supply-tube; substantially as described.

14. The combination with a cylinder, and a source of fluid-supply, a piston in said cylinder, a supply-tube in communication with said cylinder, an exhaust-tube in communication with said cylinder, a regulating device, the casing of which is in communication with both tubes, oppositely-opening check-valves in said regulating device affording communication between one of said tubes and the source of supply when the other of said tubes is closed, said casing having a valved exhaust-port between the supply-port valve and the discharge end of the supply-tube; substantially as described.

15. The combination with a cylinder and piston therein and a source of fluid-supply, of an operating-valve capable of admitting or exhausting the operating fluid from said cylinder, a tubular port connecting said operating-valve with the cylinder, regulating means in said port, for controlling the admission of fluid through the port, said means being independent of the operating-valve, regulating means in said port independent of the operating-valve for controlling the egress of fluid through said port, and a fluid cushion at the end of said cylinder connected to said port through a passage in which is a means for regulating the egress of fluid to said port; substantially as described.

16. The combination with a cylinder having a port at each end, and a piston in said cylinder and a source of fluid-supply, of an operating-valve capable of admitting or exhausting the operating fluid from said cylinder, a tubular port connecting said operating-valve with the cylinder, regulating means in said port, for controlling the admission of fluid through the port, said means being independent of the operating-valve, regulating means in said port independent of the operating-valve for controlling the egress of fluid through said port, and a fluid cushion at the end of said cylinder connected to said port through a passage in which is a means for regulating the egress of fluid to said port; substantially as described.

17. The combination of a cushioned cylinder with piston and operating-valve, of a

port with check-valve therein which can be used for exhausting only, a port with check-valve therein which can be used for admission only, and a port to dissipate the cushion; substantially as described.

18. The combination of a cushioned cylinder with piston and operating-valve, of a port with check-valve and regulating-valve therein arranged for exhausting fluid from cylinder only, a port with check-valve and regulating-valve therein arranged for admitting fluid to the cylinder only, and a port with regulating-valve therein to control the cushion; substantially as described.

19. The combination of a cushioned cylinder and piston therein, a fluid cushion at each end of the cylinder, a source of fluid-pressure supply, an operating-valve connected by a port to one end of said cylinder, an exhaust connection with check-valve and regulating means therein between said port and cylinder, an admission connection with check-valve and regulating means therein between said port and cylinder, and a connection with regulating means therein between the cylinder and port arranged to regulate the dissipation of the cushion; substantially as described.

20. The combination with a cushioned cylinder and piston therein, a fluid cushion at each end of the cylinder, and a source of fluid-pressure supply, of an operating-valve connected by a port to one end of said cylinder, an exhaust connection with check-valve and regulating means therein between said port and cylinder, an admission connection with check-valve and regulating means therein between said port and cylinder, a connection with regulating means therein between the cylinder and port arranged to regulate the dissipation of the cushion; means for regulating the escape of air from the opposite end of the cylinder to the atmosphere, and a means for regulating the dissipation of the cushion at the last-mentioned end of the cylinder; substantially as described.

21. The combination with a double-acting cushioned cylinder and piston therein and a source of fluid-pressure supply, of an operating-valve connected to said source and to both ends of the cylinder by ports, and regulatable admission, exhaust and cushion dissipating connections between each end of said cylinder and its respective port; substantially as described.

22. In a means for regulating a cushioned cylinder, the combination of an exhaust-port with check-valve and regulating device therein, an admission-port with check-valve and regulating device therein, and a cushion-dissipating port and regulating means therein; substantially as described.

23. In a means for regulating a cushioned cylinder of the class described, a casing with an exhaust connection, and an admission

connection, an operating-valve connection, a port in said casing between the exhaust and operating-valve connection, a check-valve in said port permitting exhaust of air from the cylinder but preventing admission of air to same, a means for regulating the area of the exhaust-port; a port in said casing between the admission connection and operating-valve connection, a check-valve in said port 5 permitting the admission of air to the cylinder but preventing the exhaust of air from same, a means for regulating the area of the admission-passage, a secondary port connecting the admission connection to the operating-valve connection, and a means in said 10 secondary port for regulating the area of said port; substantially as described.

24. In a means for regulating a cushioned cylinder of the class described, the combination of a casing with an operating-valve connection 23, an exhaust connection 29, and an 15

admission connection 30, a port in said casing leading from exhaust connection 29 to operating-valve connection 23, a check-valve 27 in said port, a means for limiting the maximum opening of said check-valve, a port in said casing leading from the operating-valve connection 23 to admission connection 30, a check-valve 28 in said port, a means for limiting the maximum opening of 20 said check-valve, and a secondary port between connections 23 and 30, with a means for adjusting the area of said secondary port; substantially as described.

In testimony whereof I hereunto affix my 35 signature, in the presence of two witnesses, this 21st day of November, 1905.

GEORGE F. STEEDMAN.
